UNITED STATES PATENT OFFICE.

LEWIS M. SWITZLER, OF COLUMBIA, MISSOURI.

CALENDAR.

SPECIFICATION forming part of Letters Patent No. 276,643, dated May 1, 1883.

Application filed January 31, 1883. (No model.)

To all whom it may concern:

Be it known that I, LEWIS M. SWITZLER, a citizen of the United States, residing at Columbia, in the county of Boone and State of Missouri, have invented a new and useful Calendar, of which the following is a specification, reference being had to the accompanying drawings.

This invention relates to calendars, and has for its object to provide a simple, inexpensive, and efficient perpetual memorandum-calendar that will be especially adapted for convenience in use by business men and others.

In the drawings, Figure 1 is a perspective view of my improved calendar. Fig. 2 is a longitudinal sectional view thereof. Fig. 3 is a horizontal transverse sectional view on the line *x x*, Fig. 2. Fig. 4 is a detail sectional view taken through one of the holding-staples.

Referring to the drawings, A designates a back board, on which the calendar mechanism is arranged. This back piece or board can be laid flat or inclined on a desk or table; or it can be suspended upon a hook, B, passing through a hole at its top, as shown in the drawings. The back piece may be provided with a projecting base, C, at its bottom, which will serve as a desk, or for any other purpose.

D is a casing, that is arranged at the top of the back board, and is provided with longitudinal slots E and F in its face. In this casing are journaled two rollers, G and H, having ends I projecting at the sides of the said casing, so that they may be turned by hand. On the top roller, G, are arranged the days of the week, so that they can be successively brought to view by turning the roller before the opening E. In like manner the under roller, H, carries the names of the months, so that these may be brought to view at the opening F. These rollers can be provided with separate casings, or they can be both inclosed in one casing, as shown.

Some distance below the casing D are arranged staples J J, longitudinally disposed in relation to the back board, and on these staples are strung thirty-one cards, K, each being provided with eyelets L, through which the staples pass. On one face of these cards are arranged successively the numbers of the days

of a month, from 1 to 31, while the reverse face of the cards can be used to display advertisements or other matter. The face of the cards bearing the number of the day of a month is normally exposed, and as the 55 days pass in succession the cards are turned over on the staples and hang therefrom, so as to present their advertising side to view. The numbered face of the cards is adapted to receive any desired memoranda, and the cards 60 are preferably formed of a material that will admit of the memoranda being erased to make place for other notes.

M is an inclined back or rest piece that is arranged above the staples, against which the 65 cards rest in inclined position when turned up, to obviate accidental falling over of the cards. The ends of the staples may be secured permanently to the back board, or the upper end only can be permanently secured, in which 70 case the staple will be formed of elastic wire, and its lower end will rest in a recess or perforation, N, in the back board. The lower end, O, can then be lifted out of the said perforation N, as shown in dotted lines, Fig. 4 of the 75 drawings, to admit of removal of the cards from off the staples for substitution or other purposes. Below the staples a space is provided for the attachment of a yearly calendar, P. The top edge of the staples is provided 80 with notches Q, that serve to retain the cards resting on top of the staples against accidental falling over.

R designates pen-racks of suitable construction, that are arranged transversely on the 85 back board at desired places.

The operation and advantages of my invention are obvious. It is very simple, and is of superior convenience and utility.

If desired, a series of cards similar to the 90 series above described can be arranged to indicate the months, in lieu of the month-roller.

I claim as my invention—

1. As an improvement in calendars, the combination of a vertical back piece, staples arranged on said back piece, indicating cards arranged to be successively turned over on the staples to present different sides, and an inclined back arranged above the staples, so that when the cards rest on the top of the staples 100

they will incline against this back to obviate accidental falling over, as set forth.

2. As an improvement in calendars, the combination of a back piece having recesses or 5 perforations, staples having one end secured to the back piece and the other elastic end fitting in the perforations in the latter, and adapted to be removed from the same, and indicating cards strung on the staples and 10 adapted to be removed therefrom by disengag-

ing the elastic end from the perforations, as set forth.

In testimony that I claim the foregoing as my own I have hereto affixed my signature in presence of two witnesses.

LEWIS MILTON SWITZLER.
